UNITED STATES PATENT OFFICE.

ALEXANDER S. SPIEGEL, OF CHICAGO, ILLINOIS.

MACHINE FOR MAKING ORNAMENTAL ROOFING-STRIPS.

1,110,238.

Specification of Letters Patent. Patented Sept. 8, 1914.

Application filed April 14, 1914. Serial No. 831,870.

To all whom it may concern:

Be it known that I, ALEXANDER S. SPIEGEL, a citizen of the United States, residing at Chicago, Illinois, have invented certain new and useful Improvements in Machines for Making Ornamental Roofing-Strips, of which the following is a specification.

This invention relates to the making of ornamental roofing strips and its object is to provide a cheap and efficient machine that will cut out portions of a strip of prepared roofing to give a shingle effect.

The invention consists in the construction and arrangement and combination of parts hereinafter described and particularly pointed out in the claim, it being understood that I do not intend to limit myself to the details of the different parts of my invention.

The invention is illustrated in the accompanying drawings, in which—

Figure 1 is a sectional end view of the machine. Fig. 2 is a front elevation with parts in section. Fig. 3 is a view of the roofing fed to the machine. Fig. 4 is a view of the product emerging from the machine. Fig. 5 is a view of the finished product.

In the drawings, the ordinal 1 indicates the roofing material, 2 a rotary punch member carrying cutters 3 and mounted upon a shaft 4. Similarly mounted upon a shaft 5 is a rotary die member 6 having openings 7 in its periphery, into which are arranged to extend the cutters 3 of the punch 2. The die 6 has a hub portion 8 upon the shaft 5 which has a circular enlargement 9 at one end, upon which the die proper is formed. This construction provides a space 10 between the hub 8 and the die 6 with which the openings 7 communicate for a purpose hereinafter set forth.

In operation the roofing material is previously cut into strips, as shown in Fig. 3

in any known manner, and then passed through the machine either singly or in pairs. The roofing is passed between the punch 2 and die 6 where it is acted upon by the cutters 3 of the punch 2, which in entering the openings 7 of the die 6 punch out a portion of the material of a shape as indicated at 11 in Fig. 4. The punched out pieces are pressed through the openings 7 by the cutters 3 into the space 10 from whence they fall because of the rotation of the die 6. The strips emerge from the machine as shown in Fig. 2 and when separated they constitute the finished product that is illustrated in Fig. 5.

While I have mentioned that the roofing material is cut into strips previous to its being acted upon by the machine, it may not be cut into strips until after the action of the machine upon it, if it is so desired.

I claim as my invention:

A machine for cutting rectangular openings in a roofing strip consisting of a pair of rolls one above the other, one having punches or cutters projecting from its periphery between the ends thereof and the other being hollow and having openings in its periphery registering with the punches, both rolls having cylindrical peripheries adapted to contact continuously from end to end with the material acted on, and at each end throughout their circumferences, the hollow roll having an inner tapered or conical hub for the delivery of the punched out pieces, substantially as described.

In testimony whereof, I affix my signature in presence of two witnesses.

ALEXANDER S. SPIEGEL.
